UNITED STATES PATENT OFFICE.

CHARLES LEDIN, OF STAMFORD, CONNECTICUT, ASSIGNOR TO THE YALE & TOWNE MANUFACTURING COMPANY, OF STAMFORD, CONNECTICUT.

MOUNTING MEANS FOR LOCKS.

Application filed February 13, 1925. Serial No. 8,963.

To all whom it may concern:

Be it known that I, CHARLES LEDIN, a citizen of the United States, and resident of Stamford, in the county of Fairfield and State of Connecticut, have invented certain new and useful Improvements in Mounting Means for Locks; and I do hereby declare the following to be a full, clear, and exact description of the invention, such as will enable others skilled in the art to which it appertains to make and use the same.

This invention relates to improvements in mounting means for locks and more particularly to adjustable devices for mounting a cylinder lock for use with a rim lock, in doors,—one object of the invention being to provide simple and efficient means which shall be adaptable to doors differing in thickness, for carrying a cylinder lock intended for use with a rim lock, and to so construct and arrange adjustably connected devices for a cylinder lock in a bore in a door, mounting devices that said devices cannot be rotated or moved longitudinally after having been installed.

With this and other objects in view, the invention consists in certain novel features of construction and combinations of parts as hereinafter set forth and pointed out in the claims.

In the accompanying drawings;

Figure 1 is a sectional view showing an embodiment of the invention when applied to a door of one thickness;

Figure 2 is a similar view showing the improvement applied to a door having less thickness;

Figure 3 is an outside end view;

Figure 4 is an inside end view with the cover plate of the rim lock casing removed;

Figures 5 and 6 are detail perspective views of the tubes or shell 5 and 6, and

Figure 7 is a side view.

A portion of a door is represented at 1 and is provided with a bore or opening 2 for the accommodation of the mounting devices in which a cylinder lock 3 is located. My improvements are intended for use with a rim lock and while it need not be herein shown and described, I have indicated at 4 the cover plate of a rim lock casing, with which plate, a part of the mounting device for the cylinder lock cooperates.

My improved mounting devices comprise three tubes or sleeves 5, 6 and 7. The base

tube is inserted into the bore or opening 2 in the bore, and may be somewhat shorter than the length of the latter in the case of a thick door. The tube or shell 5 with diametrically opposite series of slots or holes 8, 9,— 60 the slots or openings of each series being suitably spaced apart longitudinally of the tube or shell. The tube or sleeve 6 (which may be conveniently made of sheet metal), is provided at one end with forwardly projecting lugs 10, 11, the lugs 10 being disposed diametrically opposite each other and said lugs are adapted to project through suitable slots or openings in the cover plate 4 of the rim lock casing and riveted over 70 or not as desired. The tube or shell 6 is also provided with outwardly projecting lugs or wings 12 (which may be cut from the metal of the tube or shell and bent outwardly) and these lugs or wings will, when 75 the tube or shell 6 is passed over the tube or shell 5, rest against the inner face of the door, as illustrated in Figures 1 and 2. The tube or shell 6 is also provided with fingers or catches 13 (which may be cut from the 80 metal of said tube or shell) provided with inwardly projecting portions 14 to enter holes 8 or 9 in the base tube or shell 5.

The cylinder lock 3 is suitably secured within the base tube or shell 5, and this may 85 be accomplished by forcing parts of the metal of said tube or shell 5 into pits or depressions 16 as illustrated in Figure 4.

In applying the device to a door, the tube or shell 6 will be slipped onto the tube or 90 shell 5 and the two catches 13 bent down so that their inwardly projecting portions 14 will enter the holes or openings 8 or 9 according to the thickness of the door. This will allow the out-turned wings or lugs 12 95 to bear against the inner face of the door and the lugs or spurs 10—11 to enter the receiving slots in the cover plate 4 of the rim lock. When thus installed the tubes or shells 5 and 6 as well as the cylinder lock 100 will be prevented from turning or longitudinal movement. The cylinder ring or tubular shell 7 will be passed into the bore in the door and made to surround a portion of the base shell or tube 5 as shown in Figures 1 105 and 2 and the flange 7^a of said ring or shell 7 will engage the outer face of the door, to which it may be secured by fastening devices such as small nails 15.

In Figure 1 the devices are shown as ap- 110

plied to a thick door and the catches 13 of tube or shell 6 engaging in the slots or openings 8 of the base shell or tube 6, while in Figure 2, the application of my improvements to a thinner door and the catches 13 of tube or shell 6 engaging in the slots or opening 9 in the base shell 5. In the drawing, two slots or openings 8 and 9 are shown at opposite sides of the base tube or shell 6, but if desired, a greater number may be employed to permit relative further adjustment of these tubes or shells.

Having fully described my invention, what I claim as new and desire to secure by 15 Letters-Patent, is:—

1. Mounting devices for cylinder locks, comprising relatively adjustable tubes or shells to enter a bore in a door, one of said tubes or shells having projecting portions to 20 pass through holes in a member of a rim-lock casing, said tube or shell also having a laterally projecting member to engage a face of the door.
2. Mounting devices for a cylinder lock, comprising telescopic members relatively adjustable longitudinally and adapted to occupy a bore in a door, one of said members having forward and also lateral projections at one end adapted to be disposed 25 adjacent to and beyond a face of the door.
3. Mounting means for a cylinder lock, comprising telescopic members, one of said members having catches to adjustably engage the other member, said first-mentioned member also having forward and lateral

projections at its inner end portion adapted to be disposed adjacent to and beyond a face of the door.

4. Mounting devices for a cylinder lock, comprising telescopic tubes, one of said tubes having diametrically opposite series of holes and the other tube provided with catches to engage in any hole of each series in the first-mentioned tube, and inward and lateral projections at the inner end portion of one of 45 said tubes.

5. Mounting devices for a cylinder lock, comprising two relatively adjustable tubes, one of said tubes having engaging means for the inner face of a door and also having engaging means for a member of a rim lock casing, and a third tube embracing one of 50 said first-mentioned tubes and having a flange to be secured to the outer face of a door.

6. The combination with a member of a rim lock casing, of two telescopic tubes, means for securing said tubes together at different longitudinal adjustments, one of 55 said tubes having projections to engage a part of a rim lock casing and having other projections to engage the inner face of a door, a cylinder lock secured in one of said tubes, and a third tube embracing one of said first-mentioned tubes and adapted to be 60 secured at the outer face of a door.

In testimony whereof, I have signed this specification.

CHARLES LEDIN.
